CLAIM

The ornamental design for an axial spin centrifuge, as shown and described.

DESCRIPTION

FIG. 1 is a perspective view of an axial spin centrifuge showing our new design;

FIG. 2 is a top perspective view thereof;

FIG. 3 is a right side elevational view thereof;

FIG. 4 is a left side elevational view thereof;

FIG. 5 is a front perspective view thereof; and,

FIG. 6 is a rear perspective view thereof.
